UNITED STATES PATENT OFFICE.

JOHN ROBERTS, OF GREENWICH, CONNECTICUT.

DETACHABLE FINGER BOWL.

Application filed August 27, 1926. Serial No. 131,992.

This invention relates to improvements in detachable finger bowls for plates.

The primary object of the invention resides in a finger bowl which may be readily attached to plates for the serving of fruits or the like, whereby the user may cleanse their fingers after eating the same, which eliminates the necessity of serving the finger bowl separately after the course, thereby saving time in the serving of a meal.

Another object of the invention is the provision of a finger bowl attachment which is readily removable from the plate, so that the plate and bowl may be thoroughly cleansed after use to keep the same in a sanitary condition, and to allow the plate to be used without the attachment thereon when desired.

A further object of the invention aims to provide a finger bowl attachment which is simple in construction, inexpensive of manufacture and attractive in appearance.

With these and other objects in view, the invention resides in certain novel construction and combination and arrangement of parts, the essential features of which are hereinafter fully described, are particularly pointed out in the appended claims, and are illustrated in the accompanying drawing, in which:

Figure 1 is a perspective view of my improved finger bowl attachment shown in applied position upon a plate.

Figure 2 is a bottom plan view of the same.

Figure 3 is a vertical sectional view on the line 3—3 of Figure 1.

Figure 4 is a detail perspective view of the bowl per se.

Referring more particularly to the drawing, the reference numeral 10 designates my improved finger bowl attachment in its entirety and which is shown applied to a plate 11 of the usual well-known construction.

The attachment 10 comprises a pair of semi-circular sections 12, 12 which have one of their meeting ends hingedly connected together as at 13, whereby the two sections may be swung about the hinged joint to spread the same when attaching the device to the peripheral edge of the plate 11. The sections 12 are constructed of metal and each includes a horizontally disposed flange 14 which overlies the peripheral edge of the plate 11 and a diverging flange 15 which engages the underside edges of the plate to

prevent the attachment from being lifted from the plate when the sections are in a closed position.

The finger bowl is shown at 16 and is crescent shaped in plan to follow the contour of the plate so as not to project too far beyond the periphery of the same. The bowl is pivotally connected to one of the sections 12 adjacent the free end thereof as at 17, 65 while the inner wall of the bowl has a spring clip 18 extending therefrom for co-action with a pin or stud 19 extending from the flange 15 of the other section 12 adjacent the free end of the same. From the foregoing description, it will be seen that when the finger bowl is swung about its pivot 17 to cause the clip 18 to engage the pin 19, the sections 12 will embrace the peripheral edge of the plate and will be locked against swinging movement about the hinged joint 13.

For the purpose of relieving the strain on the pivot 17, I extend the bottom of the bowl to a plane parallel to the base of the plate so as to rest upon a supporting surface with the plate. This also prevents tipping of the plate due to the weight of the bowl and its contents. A flange 20 extends from the inner wall of the bowl and rests directly upon the flange 14 of the sections 12, which also tends to relieve the pivot 17 of any weight due to the bowl and its contents.

The finger bowl attachment may readily be removed from the plate by releasing the spring clip 18 from the stud or pin 19, then swinging the bowl 16 about its pivot 17, after which the two sections 12 are swung about the hinged joint 13 so that the flanges 15 clear the peripheral edge of the plate whereupon the attachment may be lifted clear of the same.

In practice, the attachment is applied to the plate in a manner already described, and if fruit or the like is to be served, the same is either placed directly upon the plate 11, or into another dish which in turn is set upon the plate, and the bowl 16 is filled with water. It will therefore be most convenient for a person after eating the food from the plate to dip their fingers into the bowl for cleansing.

The attachment can be made in various sizes to fit different size plates and also may be constructed of different metals. 110 The flange 14 also serves to prevent spilling of any of the contents from the plate due

to the fact that the same overhangs the sides of the plate, and if desired, the top surface of the flange may have a suitable design inscribed thereon so as to add ornamentation to the attachment and which design may be in harmony with the design on the plate.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:—

1. A device of the class described comprising a pair of hingedly connected sections adapted to engage the peripheral edge of a plate, a finger bowl, and co-acting means between said finger bowl and said sections for locking the free meeting ends of said sections together.

2. A device of the class described comprising a pair of hingedly connected sections adapted to engage the peripheral edge of a plate, a finger bowl swingingly mounted on one of said sections adjacent the free end of the same, and co-acting means between said finger bowl and the other of said sections for locking said sections together and for locking said finger bowl against swinging movement.

3. A device of the class described comprising a pair of hingedly connected sections adapted to engage the peripheral edge of a plate, a finger bowl swingingly mounted on one of said sections adjacent the free end of the same, and co-acting means between said finger bowl and the other of said sections for locking said sections together and for

locking said finger bowl against swinging movement, said co-acting means including a spring clip carried by said finger bowl, and a stud extending from said section for engagement by said spring clip.

4. An attachment of the class described comprising an annular member formed of a pair of hingedly connected sections, a finger bowl carried by the free end of one of said sections, and co-acting means between the other of said sections and said finger bowl for locking the free ends of said sections together.

5. An attachment of the class described comprising an annular member formed of a pair of hingedly connected sections, a finger bowl carried by the free end of one of said sections, and co-acting means between the other of said sections and said finger bowl for locking the free ends of said sections together, said means including a spring clip carried by said bowl for engagement with a pin on said section.

6. A device of the class described comprising a pair of pivotally connected sections, a finger bowl pivotally supported by said sections, and co-acting means for locking said sections in co-acting position.

7. A device of the class described comprising a pair of pivotally connected sections adapted to engage the peripheral edge of a plate, a finger bowl swingingly mounted on one of said sections, a flange on the inner wall of said finger bowl for overlying the joint between said sections and resting thereon when said sections are in closed position, and co-acting means for holding said sections and said finger bowl against swinging movement.

In testimony whereof I have affixed my signature.

JOHN ROBERTS.
